UNITED STATES PATENT OFFICE.

CHARLES F. LOOFBOURROW, OF OAKLAND, CALIFORNIA.

SHOE-FASTENING DEVICE.

Application filed January 20, 1928. Serial No. 248,246.

This invention relates to improvements in shoe fastening devices. This invention relates to improvements in hook eyelet found on many types of high 55

The principal object of this invention is to provide a simple device which will eliminate 5 the necessity for using shoe strings.

Another object is to provide a device which may be employed with any type of shoe for the purpose of holding the shoe upon the foot of the wearer in a manner similar to 10 that accomplished with the ordinary shoe string but without the employment of a string, thereby eliminating the danger of breakage.

A further object is to produce a device 15 which will be neat in appearance and therefore one which will not be objectionable or unsightly in use.

A still further object is to produce a device which is economical to manufacture.

20 Other objects and advantages will be apparent during the course of the following description.

In the accompanying drawings forming a 25 part of this specification and in which like numerals are employed to designate like parts throughout the same,

Figure I is a top plan view,

Figure II is a side elevation of one form 30 of my device,

Figure III is a side elevation of Figure I,

Figure IV is a bottom plan view of Figure II,

Figure V is a modified form of my fastening element, and

35 Figure VI is a perspective view of a shoe having my invention applied thereto.

It is customary to secure the ordinary shoe to the foot of the wearer by employing shoe strings for the purpose of lacing the shoe. 40 These strings often break and more often become untied, which necessitates a delay as well as the effort of repairing the lace or retying the lace.

45 Applicant has therefore devised a simple hook arrangement which may be employed with many types of shoes and one which may be quickly placed upon the shoe and quickly manipulated when fastening the shoe.

In the accompanying drawings wherein 50 for the purpose of illustration is shown a preferred embodiment of my invention, the numeral 5 designates the looped portion of one form of my device, which looped portion is adapted to be engaged with the ordinary

This ring 5 has an extension 6 which is provided with a downturned end 7 having an upturned portion 8. The result of this construction is that when the ring 5 is engaged with the hook eyelet, the extension 6 will bridge the space between the two sides of the shoe, while the end 7 will enter the hook element on the opposite side of the shoe engaging the shank portion thereof as in the recess 9. The end 8 serves to prevent the end 7 from becoming disengaged with the shank of the hook.

In the form shown in Figure II, the construction is substantially the same with the exception that the ring 5 is offset from the extension 6 by a downwardly extending portion 11. The result is that with this form of fastening element the same is best adapted for use with shoes having eyelets of the character shown in Figure VI.

The manner of applying is that the end 7 is passed upwardly through one of the eyelets from the inside of the shoe and moved so that the portion 11 will lie through the eyelet with the ring 5 underlying the flap of the shoe. The portion 6 will now bridge the opening of the shoe so that the end 7 may enter the eyelet upon the opposite side of the shoe.

85 In the form shown in Figure V I prefer to employ a flat band which is provided at one end with a return band 12 and at its opposite end a hooked extremity 13. The manner of employing this modified form is similar to that just described for Figure II.

The appearance of my fastening element is well known in Figure VI where the upper fastening element is in a position where it is just about to be fastened. The next fastening element shows the position as the same would assume when unfastened and the four lower fastening elements disclose the appearance that the fastening elements would make when in use.

100 It is to be understood that the form of my invention herewith shown and described is to be taken as a preferred example of the same and that various changes relative to the material, size, shape and arrangement of parts 105 may be resorted to without departing from the spirit of the invention or the scope of the subjoined claim.

Having thus described my invention, I claim:—

A shoe fastening element comprising a bridge portion having a down-turned end 5 said end having its extremity bent upon itself, a loop carried at the opposite end of said bridge portion and being offset relative

thereto, said loop being in parallelism to said bridge portion and lying in the same plane as the plane of the extremity of the down turned end. 10

In testimony whereof I affix my signature.

CHARLES F. LOOFOURROW.
